UNITED STATES PATENT OFFICE

FRANK DITCHFIELD, OF CLEVELAND, OHIO, ASSIGNOR TO THE YOUNGSTOWN STEEL DOOR COMPANY, OF CLEVELAND, OHIO, A CORPORATION OF OHIO

GRAIN DOOR FOR CARS

Application filed August 29, 1930. Serial No. 478,645.

This invention relates to improvements in grain doors for cars.

As well known to those skilled in the art, there has long been a demand for a satisfactory permanent type of grain door for box cars and numerous attempts have been made to supply this demand. The most common arrangement heretofore suggested has involved the use of a main panel or door section pivoted at its outer edge adjacent the side door sill, which main section or panel, when not in use as a main door, becomes a part of the car floor. Due to limitations in the width of the car, such main sections or panels cannot be made of the necessary height to close the side door opening and in order to provide for the additional height necessary when the door is in operative position, it has been customary to provide a pivoted or slidably connected auxiliary or supplemental flap or section attached to the inner or free edge of the main door section. In such constructions, the auxiliary or supplemental sections have always heretofore been folded under or disposed under the main door section or panel when the latter is in the horizontal inoperative floor position. Further, so far as I am aware, all such main door sections have heretofore been made of wood, presumably to conform to the remaining wood floor of the box car.

The types of grain doors above referred to have not proven satisfactory in service, particularly because the main wood door section or panel has its upper surface exposed when lying in the horizontal floor position and is thus subjected to wear and distortion on its upper surface. It is this upper surface of the main door section which must be placed against the door posts, fillers or car lining and door sills, in order to provide the necessary grain seal and because of the distortion and wear occurring on such surface, proper seals cannot be maintained after such doors have been in service for any length of time, thus permitting leakage of the grain, as will be apparent.

While the auxiliary or supplemental door sections are housed or protected in the former types of such grain doors, their im-

portance is considerably less than that of the main door section, the auxiliary or supplemental section being intended primarily to prevent spilling over the grain. It will further be obvious that with the former types of such grain doors, the use of metal in the exposed portions, lying in the floor position, is impracticable because of the indentation that would take place in the trucking in and out of the lading when the car is used for other purposes than that of carrying grain.

One object of my invention is to provide a grain door adapted to become a part of the floor section, when not in use as a grain door, so arranged that those surfaces used to effect sealing with the door posts, fillers or car lining, are not subject to wear or injury while in the floor position, so that a proper and efficient sealing may always be maintained when the door is in operative position.

Another object of my invention is to provide a grain door such that the main or lower portion thereof, which is subject to the maximum grain pressure, may be made of metal of relatively light weight but great rigidity and so disposed, when not in use as a grain door, that it cannot be injured or distorted from moving of the lading thereover.

A further object of my invention is to provide a grain door for box cars comprised of sections pivotally connected to each other at one set of ends, the opposite end of one section being pivotally connected to the car adjacent the door sill and the opposite end of the remaining section having a slidably guiding connection with the car side, so that both sections are always connected to the car body in any position thereof and their proper relation to each other and to the car body thereby always maintained.

Another object of my invention is to provide a grain door for box cars of that type where the door is adapted to assume a position forming a part of the car floor, the arrangement including a main section and an auxiliary section such that the auxiliary section acts as a protector of guard for the

main section when the parts are in inoperative or floor position.

A still further object of my invention is to provide a foldable grain door for box cars, which, when in an inoperative floor position, will occupy the minimum depth, so as to avoid extending too far below the floor level, where it might otherwise interfere with the usual brake rigging and other appurtenances necessarily disposed on the car beneath the floor.

In the drawings forming a part of this specification, Figure 1 is a vertical transverse sectional view of a portion of a rail-way box car taken through the side door opening thereof and showing my improvements in connection therewith, the improved grain door being there shown in operative vertical position. Figure 2 is a horizontal sectional view corresponding substantially to the section line 2—2 of Figure 1. Figure 3 is a view similar to Figure 1 but illustrating the position of the door parts when in inoperative horizontal floor position. Figure 4 is a horizontal sectional view corresponding to the section line 4—4 of Figure 3. And Figure 5 is a vertical longitudinal sectional view corresponding to the section line 5—5 of Figure 4.

In said drawings, the box car is shown as having the usual channel center sills 10—10, with cover plate 11, main wood flooring 12, channel side sills 13 and needle beams 14—14. The side of the car is or may be of common wood sheathing type, indicated at 15, wherein the door opening is defined by Z-bar vertical door post 16—16 having wood fillers 17—17. The top of the door opening is defined by a Z-bar lintel 18 and the threshold is formed by a Z 19 secured to the outer side of the side sill 13 and wood threshold proper 20, the latter being flush with the main flooring of the car. The door opening may be closed with any desired type of outside door, that shown at 21 being of the sheet metal type, which engages, at its front edge, within a front edge combined stop and sealing bar 22, the door at its rear edge having a spark seal 23 cooperable with an angular spark seal 24 secured to the rear door post 16. Said door 21 is shown as of the bottom hung type, riding upon a track 25 mounted on brackets 26 secured at intervals to the side sill 13.

In carrying out my invention, the car is provided, opposite each side door opening, with a metallic sub-flooring 27, which is in the form of a metal sheet or panel secured at its outer edge to the side sill 13, as indicated at 28, and having its inner edge resting upon the cover plate of the center sill construction, as indicated at 29. Along its side edges, the sub-flooring is supported by angles 30—30 secured to the respective needle beams 14. Said sub-flooring is pref-

erably reinforced by integral corrugations 31—31 and the outer portion of the sub-flooring is downwardly offset as clearly indicated in Figures 1 and 3, so as to provide the necessary space or clearance for the hinging of the main grain door section, hereinafter described. As clearly shown in Figure 5, the recess provided by the sub-flooring is sealed against leakage by suitable angles 30—30 having one flange of each thereof secured to the corresponding needle beam 14 and the other flange extended upwardly into a recess 51 in the car flooring.

For each side door opening of the car, I provide a grain door which comprises two sections A and B, the former being what I term the lower or main section of the grain door and the latter the supplemental or auxiliary section or panel. Said main section A is preferably composed of sheet metal, which may be made of relatively light gauge and weight and yet obtain the necessary strength to resist the fluid-like pressure of the grain or other similar type of lading. As shown, said main section A consists of a panel of sheet metal having a plurality of integrally formed corrugations 32 therein, said corrugations being so disposed that, when said section A is in horizontal position as shown in Figure 3, the corrugations extend downwardly below the main plane of the sheet metal panel and are nested within the corresponding corrugations of the sub-flooring 27. With the nested corrugations as above described and as best illustrated in Figure 3, it is evident that the total depth from the top surface of the auxiliary section B to the lower plane of the sub-flooring, is comparatively small, so that the brake rigging or any other attachments cannot possibly be interfered with. Said main section A has flat inner and outer margins 33 and 34 and flat side margins 35—35, so that, when said section A is in operative or closed position, as shown in Figure 1, the lower flat margin 33 will bear against the inner face of the wood threshold 20 and the flat side margins 35 will bear against the filler strip 17 as shown best in Figure 2, so as to thereby provide a tight grain seal around said three edges of the main section A. Said section A is pivotally connected along its outer edge to the car body, preferably by a pair of offset hinge butts 36—36 which are in turn pivotally connected to hinge brackets 37—37 secured to the side sill 13, said brackets 37 and hinge butts 36 being accommodated within the downwardly offset portion of the sub-flooring 27.

The supplemental door section B is made of wood, preferably in the form of a series of boards or planks 38—38 suitably secured together to form a complete rigid section, said section B being of an area somewhat

larger than the area of the main section A and adapted to completely overlie the latter when the door sections are in inoperative horizontal position as shown in Figure 3. Said planks are preferably reinforced and secured together by metal bindings 39 and 40 at the inner and outer edges of the section B, as best shown in Figure 3. When in horizontal inoperative position, said section B rests, at its inner edge, on furring 41 on the center sill construction, so that said section A lies flush with the main flooring 12 of the car. The outer edge of said section B is supported on the upper flange of the side sill 13 and said section lies flush with the door sill proper 20, all as clearly shown in Figure 3. Said section B is pivotally connected on its under side at a point somewhat inward of its inner edge by suitable hinges 42-42, to the inner flat marginal portion of the main section A, so that, when the two sections A and B are elevated to vertical position, as shown in Figure 1, the inner bound edge 39 of the section B will extend downwardly of and overlap the upper portion of the main section A and on the inner side of the latter so as to provide an effective grain seal along this edge. It will also be understood that the marginal portions of the section B lie flat against the lining of the car in a manner similar to that of the main section A, as heretofore described, thus providing a grain door of ample height to not only withstand the pressure of the main body of the grain but to prevent spilling.

Referring to Figure 4, I provide Z-bar guides 43-43 along each side of the door opening on the inner side of the lining and spaced sufficiently to permit the door sections A and B to move therebetween to their sealed position against the car lining or fillers 17. Said guides 43 are vertically disposed throughout the greater portion of their length, but are slightly inwardly inclined at their lower portions, as indicated at 143. Cooperable with said guides 43 are laterally extended lugs 44-44 formed on suitable castings or brackets secured to the outer or free edge of the door section B so that in any position of the door section B, a guiding slidable connection is present between said section B and the car body, as will be understood.

The two-section grain door may be elevated to its vertical operative position by any suitable means, one such means comprising a hook 45 attached to a cable 46 adapted to be drawn through a snatch-block 47, which in turn may be detachably connected to the lintel or side plate 18 by engaging an eye-bracket 49.

Where a discharge hopper is not used opposite the grain door, it is practically necessary to provide some means of relieving the

pressure of the grain on the inner side of the grain door before the latter is opened for the complete discharge of the car. For this purpose, I provide a relief door 50 near the bottom of the main grain door A, which relief door 50 may be of any suitable or desired form and in the instance shown, more or less conventionally, consists of a small sheet metal, plane panel slideable horizontally in guides 150-150 on the inner side of the main door A as shown in section in Figure 1. As will be evident, when the relief door 50 is moved lengthwise so as to uncover the relief opening in the main door A, the grain immediately behind the door will discharge by flowing out and the level of the grain behind the door lowered so that the grain door proper may be swung back sufficiently to obtain access to the interior of the car and complete discharge of the lading.

It is also desirable to temporarily hold the two parts A and B of the grain door when in their operative position before the pressure of the grain comes against the inner side thereof. Any suitable means may be employed for this purpose, one simple expedient, as illustrated, being the use of horizontally slideable bolts 51-51, one at each side of the auxiliary door B, near the bottom thereof, which bolts are positioned either flush or below the outer surface of the auxiliary door B and the ends of which are adapted to be projected into the guides 43. In this manner, the two door sections A and B will be held against any accidental displacement until the grain is filled in behind and after the latter occurs, obviously the pressure will be sufficient to keep the door sections in firmly held position against the liners or fillers 17.

When the door sections are in inoperative horizontal floor position, it will be observed that the metal main section A is completely covered and protected by the wood supplemental section B and hence the metal section is free from danger of injury or distortion. Furthermore, by making the supplemental section B of wood, the floor of the car is made of similar material throughout and should any serious wear or injury thereto occur, the wood planks can easily be replaced. It will further be noted that the surface of the supplemental section B which engages with the car lining or fillers 17 to form a seal, is on the underside when the section B is in horizontal floor position and hence is not subject to the usual wear or indentation and thus a perfect seal may always be maintained. The arrangement is relatively inexpensive; entails no material increase in cost of the car; may be incorporated in either new or old equipment; and provides a permanently attached grain door for the car body. While I have shown a

fixed sub-flooring for the car, it will be understood by those skilled in the art that the invention may be carried out in connection with a hopper for discharging the grain whenever this is desired.

I have herein shown and described what I now consider the preferred manner of carrying out my invention, but the same is merely illustrative and I contemplate all changes 10 and modifications that come within the scope of the claims appended hereto.

I claim:

1. In a car having a door opening and a floor, a grain door for closing said opening, 15 said door being comprised of a main lower section and an auxiliary upper section, said sections being arranged to assume either a vertical operative position over the door opening with the surfaces on one side thereof of adapted to engage fixed portions of the car defining the door opening to form a seal therewith, or an inoperative horizontal floor position, said auxiliary section overlying the main section when the sections are 20 in the horizontal floor position and the auxiliary section having its said seal-forming side faced downwardly to thereby prevent injury to the seal-forming surfaces of both sections.
2. In a car having a door opening and a floor, a grain door for closing said opening, said door comprising a sheet metal panel pivotally connected along its outer edge to the car, adjacent the door sill, said panel 25 being adapted to assume either a vertical operative position over the lower portion of the door and seal the same, or a horizontal position within the car; and displaceable means arranged, in one position, to cover said metal panel and protect the same from the lading when said panel is in said horizontal position and, in another position, to constitute an extension upwardly of said panel when the latter is in said vertical 30 operative position.
3. In a car having a door opening and a floor, a grain door for closing said opening, said door comprising a sheet metal panel pivotally connected along its outer edge to 35 the car, adjacent the door sill, said panel being adapted to assume either a vertical operative position over the lower portion of the door and seal the same, or a horizontal position within the car; and displaceable 40 means arranged to cover said metal panel and protect the same when said panel is in said horizontal position, said means comprising a wood panel pivotally connected to the sheet metal panel and having also an additional 45 slidable connection with the car body.
4. In a car having a door opening and a floor, a grain door for closing said opening, said door comprising a main section pivotally connected along its outer edge to 50 the car adjacent the door sill and a supple-

mental section pivotally connected to the opposite edge of said main section, said sections being substantially co-extensive in area and both pivoted to assume either a vertical operative position over the door opening 70 with the surfaces on one side thereof adapted to engage fixed portions of the car defining the door opening to form a seal therewith or an inoperative horizontal position in the floor line of the car, said supplemental section overlying the main section in said floor position and with the free edge of the supplemental section disposed adjacent the door sill, the supplemental section having its seal-forming surface faced downwardly when in floor position.

5. In a car having a door opening and a floor, a grain door for closing said opening, said door comprising a sheet metal main section and a supplemental wood section, the former being pivotally connected along one edge to the car, adjacent the door sill and the two sections being pivotally connected along the opposite edge of said main section, the flooring of the car being recessed to receive and accommodate said two sections when folded together and with the supplemental section overlying the main section, said supplemental section then forming a portion of the car floor, said sections being 90 arranged also to be disposed vertically over the door opening with the supplemental section positioned above the main section, those surfaces of the two sections which form the seal with fixed portions of the car when in 95 operative position being disposed face to face and protected from the lading when the two sections are folded to form a portion of the car floor.

6. In a car having a door opening and a floor, a grain door for closing said opening, said door comprising a main section pivotally connected along its outer edge to the car, adjacent the door sill and a supplemental section pivotally connected to the opposite edge of said main section, said sections being substantially co-extensive in area and both pivoted to assume either a vertical operative position over the door opening with the surfaces on one side thereof adapted to engage fixed portions of the car defining the door opening to form a seal therewith or an inoperative horizontal position in the floor line of the car, said supplemental section overlying the main section in said floor position with the free edge of the supplemental section disposed adjacent the door sill and the seal-forming surfaces of the two sections face to face; and cooperable means on the car body adjacent the sides of the door opening and on the free edge of said supplemental section for slidably connecting the free edge of said supplemental section to the car body.

7. In a car having a door opening and

a floor, the combination with vertical guide-
ways extending adjacent the side edges of
the door opening; of a main door section
pivotally connected to the car adjacent the
5 door sill and adapted to assume either a
vertical position over the door opening or a
horizontal position below the floor line; an
auxiliary door section pivotally connected
to the opposite edge of said main section;
10 and cooperable means on the outer free edge
of said auxiliary section slidably cooperable
with said guides, said auxiliary section over-
lying the main section when the latter is in
its said horizontal position and the then
15 upper surface of the auxiliary section being
substantially flush with the floor line.

8. In a car having a door opening and a
main floor and sub-flooring opposite the door
20 opening, and a door sill on a level with the
main flooring, the combination with a sheet
metal main door section having integrally
formed strengthening indentations and piv-
otally connected along its outer edge to the
25 car, adjacent said door sill; of a sup-
plemental wood door section pivotally con-
nected to the opposite edge of said main
section and substantially co-extensive in
area therewith, said supplemental section
30 overlying the main section when the sections
are in horizontal position and said sup-
plemental section completing the main flooring
of the car, the outer free edge of said sup-
plemental section, when in horizontal posi-
35 tion, being disposed adjacent and flush with
the door sill.

9. In a car having a door opening and a
floor, a grain door for closing said
opening, said door comprising: a main sec-
40 tion adapted to assume either a vertical
operative position to close the lower portion
of the door opening or a horizontal position
below the floor level; and displaceable means
of an area substantially co-extensive with
45 the area of said main section arranged to
cover said main door section and form a
part of the floor, when said main section is
in said horizontal inoperative position, said
means being displaceable to a vertical posi-
50 tion above said main section to close the
upper portion of the door opening.

10. In a car having a door opening and a
floor, a grain door for closing said opening
comprising: a main door section and an up-
55 per supplemental section, said two sections
being pivotally connected on the outer side
of said supplemental section at a point
above the lower edge of the latter whereby,
when in vertical operative position over the
60 door opening, the lower edge of the sup-
plemental section overlaps the upper edge of
the main section on the inner side thereof to
provide a grain seal at the joint under pres-
sure from the inside of the door, said sec-
65 tions being foldable and arranged to assume
a horizontal position in the floor line.

11. In a car having a door opening, the
combination with a corrugated sheet metal
sub-floor opposite said door opening; of a
corrugated sheet metal grain door movable
either to a vertical operative position over
70 the lower portion of the door opening to
seal the same or a horizontal floor position
superposed above said sub-floor, the corruga-
tions of said grain door and sub-floor being
so arranged that the corrugations are nested
75 when the grain door is in horizontal posi-
tion, whereby to minimize the depth of the
space required for said door and sub-floor.

12. In a car having a door opening, the
combination with a main grain door section
movably attached to the car adjacent the sill
of the door and adapted to assume either a
vertical operative position closing the lower
portion of the door opening or a horizontal
inoperative floor position; of a relief door
80 incorporated in said main door section and
movable therewith; and a supplemental door
section arranged to assume a position above
the main section when in operative position
or a position superposed above the main
85 section when the latter is in floor position,
the supplemental door section protecting the
relief door from the lading when the main
section is in said floor position.

13. In a car having a door opening, the
combination with a sheet metal main grain
door section movably attached along one
edge to the car adjacent the door sill and
movable to either vertical operative position
90 or horizontal inoperative position; of a re-
lief door mounted on and movable with
said main door section; and a supplemental
door section pivotally connected to said
main door section and adapted to fold over
95 the latter and relief door when the main
door section is in horizontal floor position.

14. In a car having a door opening, the
combination with a corrugated metal sub-
floor opposite the door opening; of a main
100 grain door section or corrugated sheet metal
movable to both vertical operative position
and horizontal inoperative position, the cor-
rugations of said section and sub-floor nest-
ing when said section is in horizontal posi-
110 tion; and a supplemental door section piv-
otally connected to the main section and
adapted to fold on top of the latter when
said main section is nested with the sub-floor.

15. In a house car having a side door
opening, the combination with a metal side
sill having an inturned upper flange dis-
posed at the bottom of the opening; of a
threshold proper for the door opening dis-
posed on top of said side sill and with its
120 inner edge outwardly offset from the inner
edge of said side sill flange; a grain door
adapted to assume an operative vertical closed
position with its lower edge against the inner
edge of said threshold and a horizontal in-
operative floor position; and means pivotally
125

connecting said lower edge of the grain door to the side sill, said means including brackets secured to the underside of said side sill flange and angular hinge butts pivotally connected to said brackets at points below the level of said side sill flange.

5 In witness that I claim the foregoing I have hereunto subscribed my name this 11th day of August, 1930.
